United States Patent Office.

JOSEPH P. DELAHENTY, OF COHOES, NEW YORK.

Design No. 3,062, dated June 2, 1868.

DESIGN FOR KNITTED FABRICS.

The Schedule referred to in these Letters Patent and making part of the same.

TO ALL WHOM IT MAY CONCERN:

Be it known that I, JOSEPH P. DELAHENTY, of Cohoes, in the county of Albany, in the State of New York, have invented a new and original Design in Patterns for Knitted Goods adapted to the manufacture of undershirts, and drawers, and ladies' skirts; and I do hereby declare the following to be a full, clear, and exact description thereof, which will enable those skilled in the art to make and use the same, reference being had to the accompanying drawings forming part of this specification.

My invention consists in the new design for patterns of knitted goods, as represented in the annexed drawing.

What I claim as new, and desire to secure by Letters Patent, is—

The design above shown and described, for a pattern for knitted goods.

JOSEPH P. DELAHENTY.
